ALEXANDER JOSEPH DERU, OF HEUSY, BELGIUM, ASSIGNOR TO SIMON DELIZE, OF PROVIDENCE, RHODE ISLAND.

Letters Patent No. 77,011, dated April 21, 1868.

IMPROVEMENT IN MACHINE FOR PREPARING WOOL, COTTON, &c.

The Schedule referred to in these Letters Patent and making part of the same.

TO ALL WHOM IT MAY CONCERN:

Be it known that I, ALEXANDER JOSEPH DERU, of Heusy, in the Kingdom of Belgium, have invented certain new and useful Improvements in Machinery for Preparing Wool, Cotton, and other material, for the process of carding; and I do hereby declare that the following is a full and correct description thereof, reference being had to the accompanying drawings, forming part of this specification, and to the letters of reference marked thereon, the same letters referring to the same parts in all the figures.

Figure 1 is a side elevation of the machine, with some parts of the casing removed to show the cylinders.

Figure 2 is a view of the other side of the machine.

Figure 3 is a top view, with the oiling-apparatus left off, and part of the top casing removed to show the cylinder.

The main objects of my improvements are to produce a more regular mode of feeding machinery for working textile and fibrous material, and also to accomplish a more thorough and uniform oiling of the material, when required, than is attained in the usual way, substituting mechanism in the place of hand-work for that purpose.

The construction and operation are as follows: A is a box or chamber to hold the wool or other material to be worked, having at its lower end the cylinder B, and also, on one side, an endless apron, C, passing down nearly to the bottom of the box, the object of which is to insure the passage downward of the material in the box to the cylinder B. A movable partition, x, is placed across the box to increase or diminish the capacity of the space occupied by the material. This partition may be kept in place by pins in the holes in the sides of the box, or by set-screws, or other convenient device, and regulates the quantity of the material taken by the cylinder B to feed the beater-cylinder, D, which is placed near enough to B to take the material from it as it revolves, and throw it upon the rolls a a a, (or endless apron,) forming a sheet, which passes through the feed-rolls, E, to the second cylinder, F, which again opens it and throws it upon the endless apron, H. Holes are made in the sides and top of the cases G and G', over the receiving-rolls or endless aprons, to facilitate the regular deposition of the material upon the aprons, by allowing the air to escape that is drawn in at the sides of the cases in which the cylinders revolve, by the centrifugal force exerted on the air in the cases by the arms of the beater. This air, rushing into the cases over the aprons, passes out of the holes, leaving the material brought in with it, deposited upon the aprons in great uniformity. The endless apron, H, delivers the sheet of material to the rollers L, S, R, that compress it to a certain extent, and pass it along to be rolled up on the movable roller K, which rests upon the two rollers M and N. A sheet of cloth, a', or other suitable substance, is fed in over the roller M to be wound up in the lap on K, to keep the different layers separate, and to prevent the drying up of the oil or moisture before the lap is carded.

The oiling-apparatus consists of the case O, in which are two cylinders, 1 and 2, having brushes on their arms. The larger cylinder, 1, is used to mix the oil and water, and deliver over the edge of the pan, c, under the smaller cylinder, 2, which takes it up, and delivers over the edge of the plate, Q, from which it runs down and falls upon the wool at t, through an opening in the case made for that purpose, just as it is passing to the beater-cylinder, D, whereby it gets thoroughly mixed by the different cylinders by the time the lap is finished.

In working cotton, the oiling-apparatus may be dispensed with, and the cylinders used with a blunt tooth, on account of injuring the staple if sharp ones are used. But for wool, a sharper tooth is necessary.

In working wool, this system of preparation has not only the advantage of saving hands and labor, but gives also a great regularity of feeding, which cannot be obtained by spreading out the wool in the usual way by hand upon an endless apron, which leaves the uniformity to depend upon the attention and skill of the person who tends the machine, and is also affected by the variable weight of the wool when it has been oiled in the usual way of five or six hundred pounds at a time, some days before working. The oiling-arrangement enables me to use oil and water as one liquid, thus diffusing or increasing the bulk of the oiling-mixture, and insuring a more thorough oiling of the whole material.

That part of the machine between the feed-rolls E and endless apron C, inclusive, may be attached directly to a carding-machine, or to a cotton-picker, or lapper, or to a wool-burring machine, in which latter case the cylinder B would be driven in an opposite direction, and an opening made in the case at z to allow the hard substances in the wool to be thrown out by the cylinder D.

The gearing, or mode of driving the different parts of the machine, may be varied according to convenience, but I will briefly describe the one used by me.

The main driving-belt drives the cylinder F, and belt from a pulley on that shaft drives the cylinder D. Both of these revolve with great rapidity. A belt, on a pulley on cylinder B, drives that cylinder by means of a pulley on the feed-rolls E, which receive motion through a gear-wheel on the other side from a pulley, and a belt from a pulley on cylinder F. The parts of the machine that wind up the lap, also the endless apron H, are driven by a belt from a pulley on the end of feed-roll E, and the oiling-apparatus is driven by a belt on a pulley, or a cone-pulley may be used, on one end of feed-roll E.

To regulate the thickness of the laps for different qualities of wool, cotton, &c., a change of wheels of different sizes is made to be put on the end of the feed-roll, E, that drives the part of the machine that winds up the laps, so that part of the machine, together with the endless apron H, may be driven faster or slower, with regard to the feed-rolls E, and the laps drawn lighter or heavier, as may be required. And a regulating-mechanism is also necessary to keep the material on the endless apron H the same thickness, as some qualities of wool, &c., will collect faster than others, and would fill the case G, so as to prevent the escape of the air, in which case the speed of the apron H and rolls should be increased.

Having thus described my improvements, what I claim as my invention, and desire to secure by Letters Patent, is—

1. I claim the combination of the case or hopper A with endless apron C and adjustable partition z, as and for the purpose set forth.
2. I claim the combination of the two cylinders D and B, with the case and endless apron C, arranged substantially as herein described, and for the purpose set forth.
3. I claim the combination of the two brush-cylinders, 1 and 2, the two reservoirs O and o, and plate Q, substantially as described, and for the purpose set forth.
4. I claim the combination of the oiling-apparatus, constructed as described, with the cylinders D and B, substantially as specified.
5. I claim, in combination, the wool-delivering or feeding-mechanism, the oiling-mechanism, the pressing and the bat or lap-forming mechanism, substantially as described, and for the purpose set forth.

A. J. DERU.
